UNITED STATES PATENT OFFICE.

EUGENE M. DAVIS, OF ALTON, ILLINOIS.

ORDERS-OUT BOOK.

SPECIFICATION forming part of Letters Patent No. 732,717, dated July 7, 1903.

Application filed January 30, 1903. Serial No. 141,138. (No model.)

To all whom it may concern:

Be it known that I, EUGENE M. DAVIS, a citizen of the United States, residing at Alton, in the county of Madison and State of Illinois, have invented certain new and useful Improvements in Orders-Out Books, of which the following is a specification.

My invention has for its object to provide an orders-out book designed to take the place of a ledger with regard to firm accounts, freight, drayage, and discount accounts on any order given. This object I accomplish by the construction shown in the accompanying drawings, in which—

15 Figure 1 shows a plan of my improved book open with the two severable sheets turned over to the right to show the ruling of the left-hand permanent sheet. Fig. 2 is a similar view with the two severable sheets turned over upon the left-hand permanent sheet and having interposed sheets of carbon and also showing the supplemental "order" and "receiving" slips. Fig. 3 is a detail view of the supplemental order and receiving slips in tablet form.

20 A designates the permanent "order-record" page, B the permanent "settlement" page, and C D the two intermediate auxiliary "severable-record" pages. The pages are thus made up in groups of four, and in such groups are placed in a suitable temporary binder, (not shown,) so that the dead pages may be removed from time to time, as will be readily understood.

25 The permanent pages A B are formed of the usual heavy ledger-paper, while the two intermediate sheets are of thin tough paper suitable for use with the carbon-paper E, as will be presently described.

30 The permanent order-record sheet A is headed "Orders" and "Order articles," "Invoice" and "Ledger." Under the heading "Order articles" the page is ruled into columns headed "Date," "Number," "No. of pieces," and "Description," while under the word "Invoice" is a column headed "Amount" and under the word "Ledger" a column headed "Charge to account of."

35 The severable leaves C D are of less length than the page A, so as to expose to view the above headings and expose horizontally-ruled spaces at the lower ends of the "Invoice"

and "Ledger" columns, which horizontal spaces are marked "Balances" and "Date," as shown in Fig. 1.

40 The leaves C D are perforated vertically near their inner edges, so as to be readily torn in that direction, while in an opposite direction the tear or severance is effected by means of a ruler or paper-cutter. The rulings on these leaves C D correspond to those on the page A, so that when the sheets C D are folded over upon page A with the carbons interposed an order written upon the uppermost page D will be duplicated also upon page C and also upon the permanent page A, as shown in the drawings.

45 The permanent page B is headed "Out," "Debits," "B/L" or "Bills of lading," "Discount," "Receiving," "Drayage," "Freight." Under the word "Debits" are columns headed "Date," "Paid by," "Amount;" under the "B/L," a column headed "Date;" under "Discount," a column headed "For cash;" under "Receiving," columns headed "Date received," "Contents checked by," "O. K'd for price by;" under "Drayage," columns headed "Amount" and "Date paid," and under "Freight" columns headed "Amount" and "Date paid." The rulings on the leaves C D also correspond to and coincide with the headings "Date," "Number," "Issued to," "No. Pcs., and "Description," and "Check here" columns on supplemental "Order" and "Receiving" slips F G made up in tablet form in alternate order. (See Fig. 3.)

50 The "Order slip" F is so headed and provided with an address-space marked "To," "Address." "Please ship to — articles specified on attached slip & charge — account." "Show our order number on invoice." "Show any items back ordered and invoice order separately without lapping orders." "Yours, truly —." "Ship by —." "Remarks —."

55 The "Receiving slip" G is so headed and is provided with a "Date received" space. "Received from — R. R. Co." "Marks —." "No. of barrels —; half barrels —; kegs —; cases —; boxes. Remarks —. Checked by —."

60 As will be seen by referring to Fig. 2, two orders have been entered numbered 1 and 2.

Order No. 1 has been torn from the severable leaves C D and pasted upon the respective order and receiving slips, while the triplicate of the said No. 1 order appears on the permanent page A. Account No. 2 has not been so transferred to the slips F G.

In Fig. 2 page B shows the "Out" side of the order No. 1 checked up from the receiving-slip G, &c.

10 The mode of operation is as follows: When goods are to be ordered, enter on the pages A C D, as before described, then tear off the orders from pages C D, and paste them upon the slips F G. The order-slip F will now be 15 mailed to the firm which is to fill the order, and the receiving-slip G will be sent to your receiving clerk. When goods are received and checked by receiving clerk, he returns it to office and bookkeeper shows date received 20 in proper place in the book opposite the proper order-number.

In tearing out the orders for pasting on auxiliary slips tear along perforated line and crosswise, using ruler. Number the next 25 order consecutively on the first full line remaining at top of portion of slip remaining in book.

When invoice is received, check with order and place total amount in proper place under column headed "Articles," "Amount." 30 In column headed "Ledger" show what account the consignment is to be charged to, whether "Expense," "Mdse.," "Advertising," &c. This is all the posting to ledger necessary. In column headed "Debits" show how paid, amount, and date. In column headed "Bills of lading" or "B/L" enter the date of same. In column headed "Discount" show amount deducted from face of invoices 35 for cash. In column headed "Receiving" post from the receiving-slip the date received, &c., as specified. In columns headed "Drayage" and "Freight" post amounts and date paid from freight-bills and dray-tickets. In 40 posting to this book post periodically, having a sticker-file for each class of papers. In the place at bottom marked "Balances" show amount of footings at different dates, and when footings of "Ledger" column and 45 "Debits" and "Discounts" columns balance the account is closed and page dead. Carry 50 forward the footings of all columns.

The advantages of this system are: It saves much posting, &c. Bills can be paid without making out an alphabetical list of same where they are paid once a month. Bills cannot be paid a second time even if unmarked duplicate is received, and freight and drayage cannot be paid a second time without the error being discovered. Order entry is saved in ledger. Current and unpaid bills are the only "alive" accounts with regard to any orders given out. All papers are handled less and with more certainty than by 65 other methods. An alphabetical index of names and orders can be kept up to date by office boy.

I claim for this system the advantages of a system for handling and keeping records of "orders out" with less work than the methods commonly employed, and the arrangement of the different pages and papers with regard to ruling, placing in position, and shifting about to suit requirements, the special ruling on all papers, column arrangement, &c., and the special arrangement of the auxiliary order and receiving slips, which are so arranged that order can be torn from book and pasted on so as to read the same as original entry left in orders-out book, with such additions as are necessary to the special requirements of order and receiving slips.

The footings of the column headed "Invoice" are the different firm credits and balance the debits of the different accounts, 85 such as merchandise, expense, advertising, &c.

Footings of the columns headed "Debit" and "Discount" are the different firm debits and balance cash, &c.

Freight and drayage debits balance cash.

Various footings should be closed and the total posted to ledger monthly.

What I claim is—

1. In a book of the character described, the 95 combination with two facing pages containing respectively columns headed for the orders to be filled and for the filled orders, of two interposed sheets between the first-named pages and lined to agree with the first-named page so that when folded over thereon with interposed carbon-sheets the written matter will appear on all three, and the auxiliary "order" and "receiving" slips having blank portions to receive the orders severed from 100 said two interposed sheets and provided with proper headings for their respective uses, substantially as described.

2. A book of the character described comprising two facing pages containing columns 110 headed for the orders to be filled and for the filled orders, two interposed sheets of less length than the first two and ruled to coincide with the column-rulings of the first page so that when folded over upon said first page 115 with interposed sheets of carbons the order written will appear on all three, and auxiliary "order" and "receiving" slips to receive the orders severed from said two interposed sheets and headed to correspond to 120 the column-headings of the first page.

3. A book of the character described comprising a page for merchandise ordered and having columns headed "Date," "Number," "Issued to," "No. of pieces," "Description," 125 "Invoice-amount" and "Ledger-charge to account of," a second page with columns headed "Debits," "Date," "Paid by" and "Amount-B/L-date," "Discount for cash," "Receiving," "Date rec'd," "Contents 130 checked by," "O. K'd for price by," "Drayage-amount, date paid," "Freight-amount, date paid," two thinner intermediate sheets ruled to correspond with the columns of the

first-named page so that when folded over thereupon with interposed sheets of carbon the matter written will appear on all three, an auxiliary "order-slip" ruled and headed to correspond with the columns and headings of the first-named sheet for the purpose described and provided also with address-spaces, directions how to ship the order and a place for signature, and an auxiliary "re-
ceiving-slip" also having columns headed to

correspond with said first-named sheet and having receipt, remark, check-receiving, and merchandise-indicating spaces for the purpose described.

In testimony whereof I affix my signature to
in presence of two witnesses.

EUGENE M. DAVIS.
